UNITED STATES PATENT OFFICE.

FRANK F. FORSHEE, OF FLINT, MICHIGAN, ASSIGNOR TO WESTINGHOUSE ELECTRIC PRODUCTS COMPANY, A CORPORATION OF MICHIGAN.

CONTACT TERMINAL.

1,424,290.

Specification of Letters Patent. Patented Aug. 1, 1922.

Application filed June 25, 1921. Serial No. 480,276.

To all whom it may concern:

Be it known that I, FRANK F. FORSHEE, a citizen of the United States, and a resident of Flint, in the county of Genesee and State 5 of Michigan, have invented a new and useful Improvement in Contact Terminals, of which the following is a specification.

My invention relates to electric heating devices and particularly to heating elements 10 for electric stoves, and it has for its object to provide new and improved contact terminals for a quickly removable heater brick of the type employed on electric stoves.

In Patent No. 1,376,415 issued May 3, 15 1921, a heater brick having a plurality of flat contact bars connected to the resistor is disclosed. The bars are located on the under surface of the heater brick with their flat surfaces parallel to that of the brick, each 20 bar being twisted through an angle of ninety degrees at a point adjacent the periphery of the brick. I have found that, when so constructed, the terminal bars absorb a relatively large amount of the heat which may 25 be radiated against the flat surface thereof by the under surface of the heater brick and, as a large proportion of this heat is conducted to the outer ends of the bars, the co-operating stationary contact terminals be- 30 come relatively hot. I have found, also, that the mechanical strength of the bars at the outer end thereof, when constructed as above described, is not as great as is desirable, and the general object of my invention 35 is to provide a construction of terminal bars which overcomes these difficulties.

In practicing my invention, I provide a heater brick, of substantially the character illustrated in the hereinbefore mentioned 40 patent, with a plurality of flat, thin terminal bars operatively connected to the resistor located in one face of a heater brick, the bars being so constructed as to have a thin edge facing the under surface of the heater 45 brick. A plurality of openings, extending laterally through the bars, is provided and the surfaces of the bars are nickel plated.

In order to maintain the outer ends of the 50 respective bars in proper operative positions relatively to the heater brick and to each other, I provide a refractory supporting member having a plurality of openings therethrough, through which the bars extend. A single resilient member is provided to permit

of clamping the supporting member against 55 the under surface of the heater brick.

In the single sheet of drawings,

Figure 1 is a bottom plan view of a complete disc heater element comprising the device embodying my invention; 60

Fig. 2 is a side elevational view of the element shown in Fig. 1;

Fig. 3 is a view, in side elevation, of the terminal-bar supporting member;

Fig. 4 is a top plan view of the member 65 illustrated in Fig. 3;

Fig. 5 is a top plan view of the resilient clamping member, and

Fig. 6 is a view, in side elevation, of the member illustrated in Fig. 5. 70

A heating element 7 for an electric stove comprises a disc 8 of a suitable refractory material having a resistor 9 located in grooves in one surface thereof.

A plurality of flat, relatively thin, terminal bars 10, 11 and 12 are connected to the resistor 9 and are located adjacent and parallel to the under surface of the disc 8. The bar 11 extends from substantially the center of the disc 8 radially outwardly to a small distance beyond its periphery. The bars 10 and 12, which are connected, at their respective inner ends, to the ends of the resistor 9 near the periphery of the disc 8, extend toward the bar 11 for a short distance 80 and are then so bent as to extend parallel thereto and project beyond the periphery of the disc substantially symmetrical with the bar 11. 85

Each of the bars is connected to the resistor 9 by means of screws or bolts 13 and nuts 14. Each of the bars 10, 11 and 12 is bent through an angle of ninety degrees near its inner end so that, while the inner end thereof has one of the flat surfaces facing the under surface of the disc, all of the rest 90 of the length of the bar has a narrow edge facing such surface. Each of the bars 10, 11 and 12 is provided with a set of holes, as shown in Fig. 2.

In operation, the under surface of the disc may reach a relatively high temperature and, therefore, may radiate heat against any object located closely adjacent thereto. However, the amount of heat which may be 105 directly radiated against the terminal bars, is relatively small by reason of the relatively small area of each bar facing the under sur-

face of the disc. The openings 15 reduce the area of the heat-conducting path, thus reducing the amount of heat which may be carried by the contact bars from the inner 5 to the outer ends thereof. It is, of course, understood that the area of cross section of the bars is still sufficiently large to conduct the current required by the resistor 9 without causing undue heating.

10 In order to still further reduce the amount of heat which may be absorbed by the respective bars, the outer surfaces thereof are polished and nickel-plated. This provides a surface for the bars which is adapted to 15 reflect the heat rather than to absorb it.

In order to secure the outer ends of the bars 10, 11 and 12, a refractory supporting member 16 is provided, having a plurality of holes 17 extending laterally therethrough, 20 the bars 10, 11 and 12 being adapted to extend through these holes. One surface of the member 16 may be substantially flat to permit of being located against the under surface of the disc 8 and one surface may be 25 so curved as to coincide with the outer periphery of the disc 8.

One of the surfaces of the member 16 and the ends thereof may be provided with a groove 18 in which is located a clamping 30 member 19, comprising a relatively thin flat metal bar, bent to substantially U-shape. Openings 20 are provided, near the ends of the member 19 to receive bolts 21 for clamping the member 19 over the member 16 to 35 hold the latter against the under surface of the disc. The middle part of the member 19 is made arcuate in contour to insure that it shall resiliently clamp the member 18 against the disc. Nuts 22 cooperate with the 40 bolts 21 to clamp the member 19 to the disc 8.

It may be noted that the device embodying my invention provides a terminal-bar construction for a quickly removable heating element which is so formed as to absorb a relatively small amount of heat from the heating element and to reduce the amount of heat conducted from the inner ends of the bars to the outer ends thereof. Inherent 45 means are also provided to reflect, rather than to absorb, heat which may be radiated against the flat surfaces of the bar. A single means is provided to hold the outer ends of the bars in proper operative position, relatively to the refractory disc and relatively to each other, and a single resilient member 50 is provided to clamp the supporting member against the surface of the disc.

Various modifications may be made in

the device embodying my invention without departing from the spirit and scope thereof and I desire that only such limitations shall be placed thereon as are imposed by the prior art or are specifically set forth in the appended claims.

60 65 I claim as my invention:

1. A heating element comprising a resistor, a refractory member for supporting said resistor, and a plurality of terminal bars on said refractory member, said terminal bars having embodying means for reducing the flow of heat to the outer ends thereof.

70 75 2. A heating element comprising a resistor, a refractory member for supporting said resistor and a plurality of flat elongated terminal bars extending parallel to one surface of said refractory member, said bars being turned edgewise to said surface.

80 85 3. A heating element comprising a resistor, a refractory member for supporting said resistor and a plurality of flat elongated terminal bars extending parallel to one surface of said refractory member, said bars being turned edgewise to said surface and having embodying means for reducing the flow of heat to the outer ends of said bars.

90 95 4. A heating element comprising a resistor, a refractory member for supporting said resistor, a plurality of terminal bars extending parallel to one surface thereof and embodying means on said bars to reduce the absorption of heat by said bars.

100 105 5. A heating element comprising a resistor, a refractory member for supporting said resistor, a plurality of flat terminal bars extending parallel to one surface of said refractory members and beyond the edge thereof and embodying means for reducing the flow of heat along said bars and further embodying means for reducing the amount of heat absorbed by said bars.

110 115 6. A heating element comprising a resistor, a refractory member for supporting said resistor, a plurality of flat terminal bars extending parallel to one surface of said refractory member and beyond the edge thereof, a refractory block having a plurality of apertures therethrough for receiving the outer portions of said bars and a single resilient member for clamping said refractory block against said refractory member.

In testimony whereof, I have hereunto subscribed my name this 16th day of June 1921.

FRANK F. FORSHEE.
